UNITED STATES PATENT OFFICE.

THOMAS MAYHEW BEAR AND JAMES PAXMAN, OF COLCHESTER, COUNTY OF ESSEX, ENGLAND.

SHAPING-MACHINE TABLE.

SPECIFICATION forming part of Letters Patent No. 415,015, dated November 12, 1889.

Application filed July 31, 1889. Serial No. 319,287. (No model.)

To all whom it may concern:

Be it known that we, THOMAS MAYHEW BEAR and JAMES PAXMAN, both subjects of Her Majesty the Queen of Great Britain, residing at Colchester, in the county of Essex, England, have invented a certain new and useful Improvement in Shaping-Machine Tables, of which the following is a specification.

Our invention relates to an improved construction and arrangement of the work-table for shaping-machines for holding and presenting the work to the cutting-tool, by which the table can be readily moved in a horizontal or vertical direction or have a circular motion given to same, so that the various faces of the work to be surfaced may be brought quickly and without resetting under the operation of the tool held on the ram-head in the usual manner.

To clearly explain the nature of our invention, reference is made to the accompanying drawings, in which—

Figure 1 is a front elevation of our improved device with the face or actual work-table and the pinion for traversing it horizontally removed. Fig. 2 is a bottom view of Fig. 1, but with the work-table in position. Fig. 3 is an elevation, partly in section, of Fig. 1, looking from the left-hand side. Fig. 4 is an elevation of the same side, also partly in section, and with the apron or casting B, hereinafter referred to, removed. Fig. 5 is an elevation of our improved device in position on a shaping-machine, a part of which only is shown. Fig. 6 is a view of same, looking from the left-hand side of Fig. 5.

To the vertical face A of a shaping-machine—such as shown in Figs. 5 and 6—we apply an apron or casting B, attached to same by means of bolt-heads a a, Figs. 3 and 6, which slide in the usual T-shaped slots of same, and which are capable of being tightened up by nuts b b, so as to fix the apron at any desired point.

In the horizontal face A we secure a rack D, with which engages a pinion d, carried in brackets d' d', forming part of the apron B. This pinion d is carried on a spindle d², Fig. 3, on which it is secured by a feather e, (shown in dotted lines,) so as to turn therewith. The spindle d² terminates in a squared

or nut-shaped head f, and may be held in the bracket below by a screw and washer, as shown. By applying a spanner to the head f the pinion d will be turned, and, engaging 55 with the rack D, will allow the apron to be traversed horizontally along the face of the bed A.

The apron B has two angle-faced slides g, with which engages a casting E, carrying a 60 circular work-table E'. This casting E has two female angled slides (not shown) cast thereon, fitting the male angled slides g g on apron B, Fig. 2, and enabling the casting E to slide vertically on B. Two portions (near the top and bottom) of each slide are cut away and fitted with four short pieces h h of angled slide or "pads," which can be firmly tightened against the slides g g by nuts and bolts passing through them 70 to fix the casting E securely in position when adjusted vertically to the required height. To perform this vertical adjustment, we employ a screwed spindle i, carried in bearings j, Figs. 1 and 3, forming part of the 75 casting E. The screw of this spindle engages with a block or nut k, having a corresponding female thread, and which forms part of the apron B. On the head of the spindle i is secured a worm-wheel l, which engages with 80 a worm m upon a spindle or shaft n, carried in suitable brackets o o o, forming part of the casting E. This shaft n terminates in a squared head, which may receive a handle n', as shown in Fig. 2. The turning of this handle will, through the worm and worm-wheel, 85 rotate the spindle i, which by rotating in the block k will be raised or lowered, and with it will raise or lower the casting E and work-table E'. This latter table has a circular 90 face, with the usual T-shaped slots for allowing the work to be fixed to same. As shown in Fig. 3, it has a boss or projection E², which passes through an opening in the casting E, and to which is secured by screws a worm-wheel p, which engages with a worm q, secured upon a shaft r, carried in brackets s s s. This shaft may terminate in a squared head similarly to the shaft n and be operated by a handle, like n', such an arrangement being shown 100 in dotted lines in Fig. 1; or it may terminate in a bevel-gear t, operated by means herein-

after described. The turning of this shaft r will, through the worm q and worm-wheel p , allow of the circular table E' being rotated so as to bring any face of the work secured on same under the action of the cutting-tool. The casting E has a projection E^3 on the lower part of same, on which rests a bridge-shaped piece u , having its upper face curved to correspond to the radius of the table E' . This bridge-piece u is capable of being raised or lowered by a wedge u^3 as it is moved forward or backward by a screw u^2 , so that when the desired position of the table and work has been attained this bridge-piece may be forced up against the edge of the table to hold it firmly in position.

When it is desired to rotate the table automatically with a step-by-step motion, so that circular work affixed thereon—such as cylinder-flanges, cross-heads, ends of connecting rods, &c.—may be readily and quickly machined, we employ an arrangement such as is illustrated in Figs. 5 and 6, in which the bevel-gear t on the shaft r gears with a bevel-gear t' on a shaft G , which, while capable of rotating same, is allowed to move vertically by its method of attachment, which consists of a feather (not shown) on the inside of same which engages with a groove t^3 on the shaft, Fig. 6. In this way the table may be raised or lowered vertically without disturbing the rotating gear. The shaft G has at its foot a bevel-gear t^3 , which engages with another bevel t^4 , secured on a shaft H . This shaft has a groove h' therein and carries a bevel h^2 , which has a feather engaging with said groove, so that the shaft may be capable of travel longitudinally when it is desired to move the work-table in that direction. The gear h^2 is driven from a ratchet-wheel K , carried on a bearing at the side of the machine through gears h^3 h^4 h^5 , the latter being on the same shaft as the ratchet, which shaft, as shown, may have a squared head for operating the parts by a handle when desired. The ratchet K is operated by a pawl k' , which is attached to a pivoted arm k^2 , operated by a rod L , which is secured to a slotted disk w , in the manner shown, so that the throw of the rod, and consequently the movement of the pawl, may be adjusted as desired. The disk w is connected to or forms part of a pinion w' , having its bearing in a bracket at the back of the machine, which pinion is driven from a second pinion w^2 on the ordi-

nary main shaft M of the machine. In this way, through the parts just described, the shaping-table E' may be given a step-by-step rotary movement, the amount of which is adjustable by the throw of the rod L , so that the face of the work affixed to the table may be presented to the cutting-tool momentarily and then moved on for a second cut parallel therewith, so that circular objects may have their radius reduced in the manner well known.

What we claim, and desire to secure by Letters Patent, is—

1. The combination, with the bed of a shaping-machine, of an apron or casting capable of longitudinal movement thereon and carrying a casting with means for giving same a vertical movement, said casting carrying a work-table with means for rotating same, substantially as described.

2. The combination, with the bed of a shaping-machine, carrying a rack D , of an apron or casting B , carrying a pinion engaging with said rack for imparting a horizontal movement to same, and a screw block or nut K , a casting E , traveling on slides on said apron and having a screwed spindle engaging with said nut K for raising and lowering said casting and means for operating same, and a circular work-table E' , carried by said casting and having a worm-wheel, with means for operating same, by which a circular motion can be given to said work-table, substantially as described.

3. The combination, with a work-table, of means for imparting thereto longitudinal and vertical movement, shafting and gears for imparting rotary movement to the said table, a rod having an adjustable throw, and a ratchet and pawl for operating the said shafting and gears through the said rod, substantially as described.

In testimony whereof we have hereunto set our hands in the presence of two subscribing witnesses.

THOMAS MAYHEW BEAR.
JAMES PAXMAN.
